PASTING MACHINE

William C. Shields, Bombay, N. Y.

Application February 27, 1934, Serial No. 713,227

3 Claims. (Cl. 91—51)

The invention relates to a pasting machine and more especially to that type of machine for the pasting together of materials, such for instance as footwear bands and soles or other articles of similar nature. The vamps or soles, which are of cloth, leather or imitation of leather, are fed into the machine from a moving table, where they are picked up by a paste roll for delivering paste thereto and subsequently stripped from the paste roll, whence they are passed along to a conveyor convenient to operators at either side thereof, where and by whom the linings are placed on the vamps, the machine operating automatically to avoid manual handling of the material and the paste applied will be uniformly delivered to the material or the work.

Another object of the invention is the provision of a machine of this character wherein the paste is uniformly fed to the material and the pasting operation carried forth with dispatch under the automatic operation of the machine, the latter being novel in make-up and in the assembly of its parts.

A further object of the invention is the provision of a machine of this character which is comparatively simple in construction, thoroughly reliable and efficacious in its working, strong, durable, and inexpensive to manufacture and install.

With these and other objects in view, the invention consists in the features of construction, combination and arrangement of parts as will be hereinafter more fully described in detail, illustrated in the accompanying drawings, which disclose the preferred embodiment of the invention, and pointed out in the claims hereunto appended.

In the accompanying drawings:

Figure 1 is a vertical longitudinal sectional view through a machine constructed in accordance with the invention.

Figure 2 is a fragmentary side elevation.

Figure 3 is a top plan view, portions being partly broken away.

Figure 4 is a view similar to Figure 5 but looking toward the opposite side of the machine.

Figure 5 is a fragmentary horizontal sectional view through the paste well or container.

Similar reference characters indicate corresponding parts throughout the several views in the drawings.

Referring to the drawings in detail, the machine comprises a main frame A of the required size and includes spaced parallel side pieces 10 joined with vertical uprights or legs 11 and 55 also transversely joined with each other in any

suitable manner. Located in this frame A, preferably at one side of the median thereof, is a paste container or well 12, this being of any approved form and open at its top, while arranged transversely of the container or well is a paste feed roller 13 having its axle 14 suitably journaled and extended beyond the opposite side pieces 10 of the frame. At one side of the roller 13 is a movable table or bed B, while at the opposite side is a traveling conveyor C, these being hereinafter 10 fully described.

The table or bed B includes a traveling endless belt supported upon rollers 15 and 16, respectively, the axle 17 of the latter being mounted in adjustable bearings 18, these being controlled 15 by set screws 19 fitted in the boxings 20 for the said bearings, the boxings being supported upon the side pieces 10 of the frame A. The axle 21 of the other roller 15, through a pulley 22 and belt connection 23, is driven from the axle 14, the 20 latter through the pulley 24 and belt 25 being driven from a power wheel 26.

The conveyor C has the endless belt 27 supported upon rollers 28 and 29, respectively, the axle 30 of the latter being mounted correspondingly to the axle 17 of the roller 15, while the axle 31 of the roller 28, through the pulley 32 and belt 33, has driven connection with the axle 14 of the paste feed roller 13, thus it being seen that the said roller 13 will simultaneously rotate 30 while the table B and conveyor C are traveling. The upper stretch of the table B is disposed in a horizontal plane elevated with relation to the upper stretch of the conveyor C, which upper stretch of the latter is likewise in a horizontal 35 plane and the inner portions of this table and conveyor overhang the container or well 12 for a distance but are slightly spaced from or removed with respect to the roller C.

Within the container or well 12 is an agitator 40 32' which through the pulley 33' and belt 34 has driven connection with the axle 14 of the roller 13, so that the agitator 32' will simultaneously operate with the table and conveyor hereinbefore described. The desired quantity of 45 paste 35 is placed within the container or well 12 and it is worked upon by the agitator 32' to maintain fluidity thereof.

Above the feed roller 13 is a spiked feed roll 36, its axle 37 being journaled in bearings, each 50 indicated at 38 and adjustably held in its companion upright 39 carried by the frame A. Each bearing is susceptible of adjustment through a set screw 40 fitted within said upright 39 and the purpose of the roll 36 is to advance material 55

over the roller 13, and such material may be 5
slipper or shoe bands 41 which are placed upon
the table B and carried thereby in the direction
of the roller 13, whence each is picked up by the
roll 36 and conveyed across such roller 13, so
that the latter may apply paste to the face of
the band at its contact side with the roller 13,
the paste 35 being delivered to the roller 13
from the container or well 12, as should be ap-
10 parent.

At the pick-up side of the roller 13 is arranged
a scraper blade 42 adjustable by a device 43
manually controlled, the blade 42 being for the
purpose of relieving excess paste from the roller
15 13 during the pick-up of the paste thereby, while
at the other side of the roller 13 is a stripper
blade 44 for stripping the work 41 from the roller
13 subsequent to the application of paste thereto
by said roller and this stripper blade directs the
20 work onto the conveyor C, whence the operators
on either or both sides of this conveyor will apply
linings to the work, thereby completing the oper-
ation of the machine.

The roll 36, through the pulley 45 and belt 46,
25 has driven connection with the axle 14, the wires
or spikes of this roll 36 functioning as pickers for
action upon the work 41 to carry it across the
roller 13 during the paste applying activity of
said roller.

The roll 36 can be termed a picker roll and the
function thereof is to hold the material evenly
onto paste roller 13 and such roll 36 can be
retarded in speed as well as advanced to any de-
gree desired to allow the paste to be applied to the
35 material by the paste roller 13 in such quantities
as may be desired and thus providing the same
effect as the material being held down on top of
paste roll unmovable until said paste roll has
worked into the material the desired amount of
40 paste necessary for the work used, or, in other
words, this picker roll not moving at the same
speed to conform with the paste roller allows the
paste to be brushed into the material to the
extent necessary for said material.

45 What is claimed is:

1. A machine of the character described com-
prising a frame, endless movable belts supported
in the frame in spaced relation to each other and
disposed for travel in a longitudinal direction,
50 one of the belts being in a plane elevated with
respect to the plane of the other belt, a paste
container arranged beneath the belts and bridg-
ing the space therebetween, a paste applying
55 roller occupying a portion of the space between
the belts and receiving paste from said container
for the application of paste to a piece of work
when passing from the higher belt to the lower
belt, a scraper blade acting upon the said roller

at that side approached by the work, a stripper
blade coacting with the roller at the side thereof
from which the work is delivered and directing
said work onto the lowermost belt, and a picker
5 roll arranged directly above the paste applying
roller and having picker fingers entirely about the
same for engagement with the work when upon
the paste applying roller.

2. A machine of the character described com-
prising a frame, endless movable belts supported
in the frame in spaced relation to each other and
disposed for travel in a longitudinal direction,
one of the belts being in a plane elevated with
respect to the plane of the other belt, a paste
15 container arranged beneath the belts and bridg-
ing the space therebetween, a paste applying
roller occupying a portion of the space between
the belts and receiving paste from said container
for the application of paste to a piece of work
20 when passing from the higher belt to the lower
belt, a scraper blade acting upon the said roller
at that side approached by the work, a stripper
blade coacting with the roller at the side thereof
from which the work is delivered and directing
25 said work onto the lowermost belt, a picker roll
arranged directly above the paste applying roller
and having picker fingers entirely about the same
for engagement with the work when upon the
paste applying roller, and means acting upon the
30 picker roll to vary the contact thereof with the
work.

3. A machine of the character described com-
prising a frame, endless movable belts supported
in the frame in spaced relation to each other and
disposed for travel in a longitudinal direction,
35 one of the belts being in a plane elevated with
respect to the plane of the other belt, a paste
container arranged beneath the belts and bridg-
ing the space therebetween, a paste applying roller
occupying a portion of the space between the
40 belts and receiving paste from said container for
the application of paste to a piece of work when
passing from the higher belt to the lower belt, a
scraper blade acting upon the said roller at that
45 side approached by the work, a stripper blade
coacting with the roller at the side thereof from
which the work is delivered and directing said
work onto the lowermost belt, a picker roll ar-
ranged directly above the paste applying roller
50 and having picker fingers entirely about the
same for engagement with the work when upon
the paste applying roller, means acting upon the
picker roll to vary the contact thereof with the
work, and an endless belt-like agitator arranged
55 within the container to have a portion adjacent
to said paste applying roller.

WILLIAM C. SHIELDS.
